UNITED STATES PATENT OFFICE

FRED L. MILLS, OF OAK PARK, ILLINOIS, ASSIGNOR TO MILLS NOVELTY COMPANY, OF CHICAGO, ILLINOIS, A CORPORATION OF ILLINOIS

COIN-CONTROLLED VENDING MACHINE

Application filed July 12, 1928. Serial No. 292,237.

This invention relates to coin-controlled vending machines, and more particularly to that type of machine in which a plurality of rotatable reels are employed in conjunction with vending mechanism and devices for delivering annular checks, or other articles, from the machine, the operation of said devices being controlled by said reels.

The object of the invention is to provide improved means whereby the rotation of the reels may be manually stopped through the exercise of skill, and the operation of said devices thus rendered subject to the skill of the operator.

15 The manual stop devices are independent of the usual mechanism for automatically arresting the rotation of the reels and in the present machine, provision is made for rendering the operation of the manual stop devices compulsory, this being accomplished by so relating the manual and automatic stop devices to the reels that the latter will be stopped in neutral, or ineffective, position upon operation of the automatic stopping devices, which, as will be understood, stop the reels only in the event of failure of the operator to stop them manually. In other words, the positions at which the reels may be arrested by operation of the manual stop devices are such as to permit operation of the delivery devices, and the positions at which said reels are stopped by the automatic stop mechanism (which stops the reels only in the event they are not stopped by the manual devices) are neutral positions which prevent the operation of said delivery devices.

A further object of the invention is to provide, in combination with the manually controlled stop mechanism, a device for preventing operation of said mechanism until after predetermined rotation of the reels, so that the latter cannot be held in the same position during successive operations of the machines.

Other objects and advantages of the invention will be apparent as it is better understood from the following description, which, taken in connection with the accom-

panying drawings, illustrates the preferred embodiment thereof.

Referring to the drawings, Figure 1 is a front elevation of a machine in which my invention is embodied, the casing being removed and certain parts broken away for convenience in illustration; Fig. 2 is a side elevation, taken from the right in Fig. 1;

Fig. 3 is a vertical sectional view, taken substantially on the section line 3—3 in Fig. 1 and showing in side elevation the device provided by my invention;

Fig. 4 is a similar view, illustrating two stages of the operation of said device, certain parts of the machine as shown in the preceding figures being omitted and others shown diagrammatically in this view;

Fig. 5 is a like view, showing still another stage in the operation; and

Fig. 6 is a plan view of the clock arm and associated mechanism for controlling certain operations of the machine.

The machine shown in the drawings as an illustrative embodiment of the invention is of the coin-controlled type and is adapted to be actuated by mechanism which is illustrated in Figs. 1 and 2. A hand operated lever 11, mounted on the interior of the casing 12, is connected with a crank (not shown) on the exterior of the casing, and is provided with a lug 13 adapted to engage a projection 14 on a lever 15, pivotally secured at 16 to a framepart 17, said lever being equipped with a laterally projecting lug 18 on the opposite side thereof from the projection 14, as clearly shown in Fig. 1. The lug 18 normally engages the upper part of a stop lever 19, which has a pin and slot connection at 21 with an intermediately pivoted lever 22, the upper end of which is provided with a pin 23, adapted to enter a coin slot 24 in a coin slot bracket 25 at the top of the machine. The upper end of the lever 19 is connected by a spring 26 with the frame and is thus held in engagement with the lug 18 on the actuating lever 15, said lever being normally held in raised position by

means of a spring 27 connected at one end to said lever, as indicated at 28, and at the 95 100

other end to a fixed point on the frame, as indicated at 29.

Said stop lever 19 is curved outwardly from the point of normal engagement with the lug 18, as shown at 31 in Fig. 2, and is provided with a shoulder 32 just beneath the curved portion 31. Downward movement of the lever 15 produced by actuation of the crank on the outside of the casing 10 permits the stop lever 19 to be drawn inwardly by means of the spring 26, provided there is no coin in the coin slot, and the downward movement of the lever 15 may continue only until the lug 18 engages the shoulder 32 on the stop lever 19. The inward movement of the lever 19 is accompanied by a pivotal movement of the lever 22, the pin 23 on said lever 22 being adapted to pass forwardly through the coin slot during this action. If there be a coin in the slot, however, it obstructs the movement of said pin 23, holding the same and the levers 22 and 19 in the position shown in Fig. 2, and the lever 15 may then be moved downwardly, past the shoulder 32, which will be cleared since the lever 19 cannot move inwardly, as above described.

The lever 15 is connected with a link 33, which has a slot 34 at the lower end thereof 30 within which is disposed a pin 35, which projects from the lever 15 and has thereon a washer 36 serving to hold the slotted part of the link 33 upon the pin 35, said pin also carrying a clip 37, which is connected by springs 38 with a plate 39 secured to an intermediate part of the link 33, thereby providing a yielding connection between the lever 15 and the link 33.

The upper end of the link 33 is turned, as indicated at 41, and is connected with a lever 42, which has a rearwardly turned end part, disposed in the slot 24 and adapted when moved downwardly to engage the coin which rests upon a yieldable support in the slot, 45 downward movement of said lever 42 serving to force said coin through the slot.

A coin chute 43 is provided to receive the coins and direct them to a suitable coin box (not shown), and the machine is or may be 50 also equipped with a tube, or magazine, 44 for receiving annular checks, if the machine is constructed for actuation by such checks, as may be the case. The tube or magazine 44 leads to a series of delivery slides 45, which are controlled, in manner not specifically illustrated, by means of a series of actuating levers 46 adapted to actuate associated stop members 47, which normally hold the slides against the tension of springs 48, 55 by which they are adapted to be actuated when released, this construction being old and being illustrated, for example, in Patent No. 1,697,537.

If there be a coin in the slot when the 60 machine is actuated, the lever 15, as pre-

viously stated, may be moved downwardly beyond the shoulder 32, and when so moved, an actuating pawl 49, carried upon a member 51, rigid with the lever 15, engages an arm 52, which is carried upon a rock shaft 53, which serves to actuate the various instrumentalities of the machine. Said rock shaft carries an arm 54, which is connected with an actuating pawl 55, which has a hook 56 at the upper end thereof adapted, when lifted by the rocking of the shaft 53 as just described, to engage teeth 57 on a series of disks 58, which are secured respectively to concentric shafts, each of which carries a reel 59, of which three are shown in the drawings, there being one of said reels and one of said disks 58 upon each shaft and the shafts being journaled in the upright 17 and an upright 61.

After being rocked by means of the actuating pawl 49, the rock shaft 53 and the actuating members carried thereby, are adapted to be returned to normal position by spring means, to be presently described, the return movement being through a quick snap action, which causes the pawl 55 to exert a quick jerk upon the disks 58, thereby starting the same and the reels 59 to rotating.

The rock shaft 53 also carries an actuating cam 62, which, when raised by rotation of the rock shaft, is adapted to engage lips 63 upon laterally projecting arms 64 of automatic stop members 65 (see Fig. 3), of which one is provided for each reel 59. Springs 66, having their opposite arms connected respectively to the member 62 and to fixed points in the lower part of the frame, tend to draw said member 62 downwardly, thus serving to return the rock shaft 53 to normal position after actuation.

The automatic stop levers 65 are pivoted on a fixed shaft 67, and as they are of duplicate construction, they will be described in the singular. A head, or stop lug 68, is carried at the upper end of the member 65 and adapted to enter between the teeth of the star wheel 69, which is fixed to one of the reels 59. A spring 71, connected at its upper end to a projection 72 on the arm 64 and at its lower end to a rod 73, tends to hold said stop member in the position shown in Fig. 3 with the stop lug 68 in engagement with the star wheel, thus holding the reel stationary.

Upon actuation of the rock shaft, the member 62, acting upon the lip 63 of the arm 64 of the stop member 65, causes the latter to turn on its pivot to the dotted line position shown in Fig. 4. At the same time, a clock arm 74, which is horizontally disposed in the lower part of the machine and pivoted at 75 to a fixed framepart 76, is moved toward the right, viewing Figs. 3, 4, and 5, and is thus positioned beneath an

angular end part 77 at the lower end of the member 65 below the pivot 67 thereof. Said clock arm is moved forwardly by means of an actuating arm 78, carried by the rock shaft 53 and adapted to engage a lug 79 on a horizontally pivoted lever 81, which is connected by an offset link 82 with said clock arm 74. After being moved forwardly to the dotted line position shown in Fig. 6, 5 said arm is slowly turned to the full line position shown in said figure by means of a spring 83, which is connected at one end to a hook 84 on said arm and at the opposite end to a lug 85 on the framepart 76, the return 10 movement being governed by means of a clock mechanism (not shown), the gearing of which is disposed within a housing 86. The link 82 is pivotally connected at 87 to said clock arm or bar 74, and said bar has a 15 guide lug 88, extending forwardly therefrom and turned downwardly, the lower part thereof being disposed within a slot 89 in a floor piece 91. There are also two other 20 forwardly extending lugs 92 and 93 on said clock arm adapted, respectively, to be engaged by the portions 77 of the stop members 65, the construction and operation of the 25 clock arm being such as to cause the stop member at the left of Fig. 6 to first drop off 30 said arm, thus permitting the stop member to be thrown into engagement with the star wheel 69 by means of the spring 71, the middle stop member being next released for like 35 action, which is followed by the release of the third stop member, so that the reels, beginning with the one at the left in Fig. 1, are 40 successively stopped automatically if they are not first manually stopped by means of manually operated stop mechanism, which will next be described.

A second stop lever 94 (see Fig. 3) is pivoted at 95 to a framepart 96 and is provided with a head or stop lug 97, which is urged toward the star wheel 69 by means of 45 a spring 98, connected at one end to a tail part 99 of said lever 94 and at the opposite end to a flange 101 on the outer end of an arm 102 on the bracket 96. Said lever 94 has a downwardly projecting part 103 beneath the pivot 95, which part is connected by means of a link 104 with an arm 105 rigid with the rock shaft 53, whereby rotation of the rock shaft in counter-clockwise direction, viewing, for example, Fig. 4, will cause 50 said stop lever 94 to be moved to the dotted line position shown in said Fig. 4.

Said lever 94 has a lug 106 projecting laterally therefrom, and this lug is adapted to be engaged by a latch member 107, which is pivoted at 108 to the framepart 96 and is adapted to be urged toward the right, as shown in the drawings, by means of a spring 109, connected at one end to an arm 111 integral with the latch member 107 and connected at the opposite end to the bracket 96. 55

The latch member 107 is also integral with, or rigid with a member 112 extending upwardly from the pivot 108 and having a flat top part 113 adapted to be engaged by a plunger 114 extending through the casing 70 115 and having a head or button 116 disposed above the top of the casing, said plunger being adapted to be normally held in the raised position as shown in Fig. 3 by means of a spring 117 disposed within a 75 housing 118 in the casing and compressed between a flange 119 of the button 116 and the base 121 of the housing 118. A pin 122, carried by the plunger 114, limits the upward movement of the latter. It will be 80 understood, of course, that there is one of these plungers for each of the reels and that the manual stop mechanism is duplicated for each reel.

The parts having moved to the dotted line 85 position shown in Fig. 4, the latch member 107 bears against the lug 106 on the stop lever 94, the point of engagement being beneath a shoulder 123 on said latch member 107. When the rock shaft 53 returns to the 90 normal position shown in full lines in Fig. 4, the stop lever 94 moves upwardly to the full line position shown in said figure, being urged in this direction by the spring 98 and being retained in this position by engagement of the lug 106 with the shoulder 95 123 and also by engagement of said lug with a shoulder 124 on a member 125 carried by the pivot 108 and having its lower end connected by a link 126 with the automatic stop 100 member 65. Movement of the clock arm 74 toward the left (viewing Fig. 4) begins immediately after release of the actuating mechanism, and when the retrograde movement has continued sufficiently to cause a 105 lug 127 to drop off said arm 74, as shown in the full line position in said Fig. 4, the stop member 65 moves under the action of the spring 71 to the full line position shown in said figure, thus disengaging the member 110 125 from the lug 106 through the instrumentality of the link 126.

The latch member 107 is adapted to be disengaged from the lug 106 through manual depression of the plunger 114, which 115 moves said latch member to the left against the tension of the spring 109. The stop lever 94 being thus released snaps into locking position through the action of the spring 98, the stop lug 97 entering between the 120 teeth of the star wheel 69. In case the plunger 114 be actuated to release the latch 107 from the lug 106 before the latch 125 has been automatically disengaged, as previously described, the stop lever 94 will be 125 nevertheless held out of action until said latch 125 has been disengaged.

After both latches 107 and 125 have been disengaged from the lug 106, as shown in Fig. 5, the stop member 94 will snap into 130

locking position through the action of the spring 98, as above stated, the parts then assuming the relation shown in said Fig. 5. In case the manual stop is not operated, the 5 reels will be stopped by the automatic stop, in which event the parts will assume the relation shown in Fig. 3. The next actuation of the rock shaft 53 will carry the stop lever 94 down to the dotted line position of Fig. 10 4, the latches 107 and 125 being at the same time moved to the position shown in said Fig. 4, in which position both latches engage the lug 106 upon the initial upward movement of the lever 94, holding said lever 15 with the stop lug 97 thereon out of engagement with the star wheel until said latches are released, in manner previously described.

Referring to Fig. 1, it will be observed that each reel 59 contains a series of symbols, or legends 128, which are adapted to be displayed through a window 129 (shown in Fig. 3), the symbols on different reels being adapted to be presented in various combinations through said window. The 20 symbols in the machine of my invention are spaced sufficiently so that blank spaces are presented to the window when the reel is stopped by the automatic stop member 65, the symbols being displayed only when the 25 reel is stopped by the manual stop member 94. Inasmuch as the position of the reels 59 and the disks 58, which are provided with openings 131 cooperating with the levers 46, controls the operation of the delivery mechanism 45, the latter may thus be prevented from operating except when the reels are stopped in position with the symbols displayed through the window 129, which, as just stated, can be accomplished only 30 through operation of the manual stop device. In this manner the use of said device is rendered compulsory and the outcome of the operation of the machine is therefore rendered necessarily subject to the 35 skill of the operator, who, by watching the symbols on the reels, may, through the exercise of skill, stop said reels so that desired combinations of symbols may be presented at the window and corresponding operations of the machine produced.

50 The operation of the machine will be understood from the foregoing description and may be briefly stated as follows:

Upon insertion of a coin in the coin slot 25 and actuation of the crank on the exterior of the casing, the lever 15 (Fig. 2) will be moved downwardly, the shoulder 32 of the lever 19 being held out of the path of the lug 18 on the lever 15 by means of the coin in the slot, as has previously been described. This downward movement of the lever 15 causes the dog 49 on the member 51 to engage the arm 52 on the rock shaft 53, rotation of said shaft serving to actuate the 55 pawl 55 to rotate the disks 58 and the reels

59 and serving also to move the automatic stop lever 65 and the manual stop lever 94 out of engagement with the star wheel 69, the actuation of the automatic stop lever being caused by the member 62 on the lip 63 70 of the arm 64 and the actuation of the manual stop lever being produced through the link 104. This actuation of the stop levers is accompanied by movement of the latches 107 and 125 into position to be engaged by 75 the lug 106 on the stop lever 94 when the latter is released. At the same time, the clock arm 74 is advanced by means of the actuating arm 78 (Fig. 3) on the rock shaft 53 and begins to slowly recede under the 80 influence of the spring 83 and the control of the governor or clock mechanism contained within the housing 86. As soon as 85 said clock arm has receded sufficiently to permit the lug 127, which, as shown, is formed on the member 132 adjustably secured to the portion 77 of the member 65 as indicated at 133, to drop off the offset arm, as shown in Fig. 4, the latch 125 is disengaged automatically from the lug 106. It 90 will be apparent that until this disengagement is effected, however, the reels cannot be stopped by the manual stop mechanism, thus insuring that there will always be a certain amount of rotation of the reels, thus preventing their being held indefinitely in a position with a desired combination of 95 legends displayed through the window 129. Actuation of the plunger 114 disengages the latch 107, permitting the stop lever 94 to 100 snap into locking position. The manual operation may be repeated to stop the other reels whenever the associated latch 125 has been released through the movement of the 105 clock arm 74, it being understood that the lugs 127 on the second and third stop members successively drop off the clock arm lugs 92 and 93, respectively, thus permitting the 110 operation of the manual stop lever 94 when released by the manually operated latch 107. The lugs 127 on the stop members 65 are at 115 an intermediate point, and it is therefore some time after said lugs drop off the clock arm before the stop member is released for engagement with the star wheel, since sufficient pivotal movement of the stop levers 65 to cause the stop lug 68 to engage the star wheel is not possible until the clock arm has passed entirely beyond the portion 77 of 120 said stop members.

The reels having been stopped by either the automatic or manual stop members, both said members will be returned to the position shown in dotted lines in Fig. 4 upon the next actuation of the machine and the operations just described will be repeated.

It is thought that the invention and many of its attendant advantages will be understood from the foregoing description, and it will be apparent that various changes may 130

be made in the form, construction, and arrangement of the parts without departing from the spirit or scope of the invention, or sacrificing all of its material advantages, the 5 form hereinbefore described being merely a preferred embodiment thereof.

I claim:

1. A machine comprising a plurality of rotatable reels, dispensing mechanism controlled by said reels, means for setting said reels in motion, automatic devices for stopping the rotation of said reels, and manually operable devices whereby the reels may be stopped independently of said automatic 10 stopping means, said last-mentioned devices comprising a stop member on the reel, a spring-projected stop lever, a latch normally holding said lever out of action, and a member adapted to be actuated by the operator for releasing said latch.
2. A machine comprising a plurality of rotatable reels, dispensing mechanism controlled by said reels, means for setting said reels in motion, automatic devices for stopping the rotation of said reels, and manually operable devices whereby the reels may be stopped independently of said automatic 15 stopping means, said last-mentioned devices comprising a stop member on the reel, a stop member adapted to be actuated by the operator for releasing said latch, and a second latch adapted to engage said lever during the initial operation of the machine and to be automatically disengaged therefrom after predetermined rotation of the reels.
3. A machine comprising a plurality of 20 rotatable reels, dispensing mechanism controlled by said reels, means for setting said reels in motion, automatic devices for stopping the rotation of said reels, and manually operable devices whereby the reels may be stopped independently of said automatic 25 stopping means, said last-mentioned devices comprising a stop member on the reel, a spring-projected stop lever, a latch normally holding said lever out of action, and a member adapted to be actuated by the operator for releasing said latch, said automatic and 30 manual stop devices being adapted to stop said reels in neutral and operative positions, respectively.
4. A machine comprising a plurality of 35 rotatable reels, dispensing mechanism controlled by said reels, means for setting said reels in motion, automatic devices for stopping the rotation of said reels, and manually operable devices whereby the reels may be stopped independently of said automatic 40 stopping means, said last-mentioned devices comprising a stop member on the reel, a spring-projected stop lever movable into engagement with said member, means operable 45

through actuation of the machine for withdrawing said stop lever from engagement with said member, a latch adapted to engage said lever when the latter is so withdrawn, and a manually operable member operatively connected with said latch and adapted when actuated to disengage said latch from said lever to permit the latter to be spring-projected into engagement with the stop member on the reel to thereby stop the rotation 50 of the latter.

5. A machine comprising a plurality of rotatable reels, dispensing mechanism controlled by said reels, means for setting said reels in motion, automatic devices for stopping the rotation of said reels, and manually operable devices whereby the reels may be stopped independently of said automatic 55 stopping means, said last-mentioned devices comprising a stop member on the reel, a stop lever forming a part of said automatic stop device, a stop lever forming a part of said manual stop device, means operable upon actuation of the machine for removing both said stop levers from said stop member, means for engaging said manual stop lever and holding the same out of action against the tension of its spring, a clock arm adapted to hold said automatic stop lever out of engagement with the stop member for a predetermined period of time during which the manual stop devices may be actuated, and means subject to the control of the operator for causing operation of said manual stop devices.

6. A machine comprising a plurality of rotatable reels, dispensing mechanism controlled by said reels, means for setting said reels in motion, automatic devices for stopping the rotation of said reels, and manually operable devices whereby the reels may be stopped independently of said automatic 60 stopping means, said last-mentioned devices comprising a stop member on the reel, a stop lever forming a part of said automatic stop device, a stop lever forming a part of said manual stop device, means operable upon actuation of the machine for removing both said stop levers from said stop member, means for engaging said manual stop lever and holding the same out of action against the tension of its spring, a clock arm adapted to hold said automatic stop lever out of engagement with the stop member for 65 a predetermined period of time during which the manual stop devices may be actuated, said automatic stop lever having a preliminary movement prior to being released for stopping the reel, means subject to the control of the operator for causing operation of said manual stop devices, and a member connected with said automatic stop lever and adapted to hold said manual stop lever out of action until said preliminary movement of said automatic stop lever.

7. A machine comprising a plurality of rotatable reels, dispensing mechanism controlled by said reels, means for setting said reels in motion, automatic devices for stopping the rotation of said reels, and manually operable devices whereby the reels may be stopped independently of said automatic stopping means, said last-mentioned devices comprising a stop member on the reel, a pivoted stop lever, means for projecting said lever into engagement with said stop member, means for withdrawing said lever from engagement with said member upon initial actuation of the machine, a latch member adapted to engage said lever when so withdrawn, a spring connected with said latch member for urging the same into engaging position, and devices subject to the control of the operator for releasing said latch to permit said stop lever to move into engagement with said stop member on the reel.

8. A machine comprising a plurality of rotatable reels, dispensing mechanism controlled by said reels, means for setting said reels in motion, automatic devices for stopping the rotation of said reels, and manually operable devices whereby the reels may be stopped independently of said automatic stopping means, said last-mentioned devices comprising a stop member on the reel, a pivoted stop lever, means for projecting said lever into engagement with said stop member, means for withdrawing said lever from engagement with said member upon initial actuation of the machine, a latch member adapted to engage said lever when so withdrawn, a spring connected with said latch member for urging the same into engaging position, devices subject to the control of the operator for releasing said latch to permit said stop lever to move into engagement with said stop member on the reel, and a supplementary latch member moved into engagement with said stop lever during the initial operation of the machine and automatically moved out of engagement therewith after predetermined rotation of the reels.

9. A machine comprising a plurality of rotatable reels, dispensing mechanism controlled by said reels, means for setting said reels in motion, automatic devices for stopping the rotation of said reels, and manually operable devices whereby the reels may be stopped independently of said automatic stopping means, said last-mentioned devices comprising a stop member on the reel, a spring-projected stop lever, a latch normally holding said lever out of action, and a member adapted to be actuated by the operator for releasing said latch, said stop devices being duplicated for each of said reels.

In witness whereof, I hereunto subscribe my name to this specification.

FRED L. MILLS.
